Des. 204,033
Patented Mar. 8, 1966

204,033

SLIDE CARRYING DISC

Walter J. Hall, Chicago, Ill., assignor to Sawyer's, Inc.,
Portland, Oreg., a corporation of Oregon

Filed Apr. 30, 1965, Ser. No. 85,035

Term of patent 14 years

(Cl. D61—1)

—Fig. 1.

Des. 204,033

PAGE 2

FIG. 2.

FIG. 3.

FIG. 1 is a front elevational view of a slide carrying disc embodying my new design;

FIG. 2 is a rear elevational view thereof; and

FIG. 3 is a perspective view thereof.

I claim:

The ornamental design for a slide carrying disc, substantially as shown.
